UNITED STATES PATENT OFFICE

JOHN A. MCKAY AND PATRICK H. LYNCH, OF DUNN, NORTH CAROLINA.

FERTILIZER DISTRIBUTOR

Application filed May 27, 1930. Serial No. 456,194.

This invention relates to fertilizer distributors or the like, and more particularly to machines of this character which are adapted for distributing fertilizer in a single row.

5 Among the objects of the invention are to provide improved gearing for driving the hopper discharging mechanism and an improved housing for such gearing, as well as to devise other practical details of construction.

In order that the invention may be readily understood, reference is had to the accompanying drawing, in which:

Figure 1 is an inverted fragmentary plan view of a machine constructed in accordance with our invention, parts being in section; and

Figure 2 is a side elevation of the same, parts being in section.

20 Referring to the drawing in detail, our improved machine comprises a pair of longitudinally extending frame members 1 secured together at their forward end and connected to a pull iron 2.

25 Supported between the frame members 1 is a casting 3 constituting the bottom of a sheet metal hopper 10. This hopper bottom is provided with a discharge slot 4, extending transversely across the same but disposed at 30 an angle to the axis of the machine, as clearly shown in Figure 1. The effective width of the slot and the rate of discharge of material therefrom is controlled by a sliding cut-off 5, connected by links 6 to a swinging bail 7, having at one side a handle or lever 8 extending upwardly along the hopper and arranged to engage a locking rack 9. This sliding cut-off and associated parts is the same as that disclosed in our copending application, 40 Serial No. 456,193, filed of even date herein- with.

Near the forward end of the frame of the machine is a ground wheel 11, rigidly secured to a shaft 12, journaled at one end in a bearing bracket 13, bolted to one of the frame members. The other end of the shaft 12 is journaled in a combined bearing bracket and housing section 14 of substantially 50 circular shape, having an upper portion

which is bolted to the other frame member 1, by means of bolts 15 and 16.

At the rear side of the housing section 14, there is formed a half bearing 17 in which the forward end of a shaft 18 is journaled. To 55 this shaft, inside of the housing section 14, is secured a bevelled pinion 19, which meshes with a bevelled gear 20 detachably secured directly to the ground wheel 11, as by means of bolts 21. We regard this method of de- 60 tachably connecting this gear to the ground wheel as a distinct advantage over the common method of casting such gear integral with the wheel, because our improved construction permits of readily renewing the 65 gear, should it become broken or worn.

Positioned outside of the housing section 14 and secured thereto by bolts 16 and 23 (see Figure 2) is another housing section or cover plate 22, of such size and construction as to 70 completely enclose the pinion 19. The rear of this housing section or cover plate is shaped at 22^a to form another half bearing for the shaft 18. Thus, this shaft is journaled in a bearing formed jointly by the 75 two housing sections 14 and 22.

By reference to Figure 1, it will be particularly noted that the forward surface of the housing section or cover plate 22, which projects laterally beyond the frame member 1, 80 is inclined and extends outwardly and rearwardly so as to present a diagonal or bevelled surface. With a housing shaped in this way, it is obvious that should an obstruction, such as a stump or the like, be encountered, as the 85 machine travels along, such obstruction will engage this inclined surface 22 and thus either the obstruction or the machine will be deflected to one side, whereby breakage or damage is avoided.

The rear end of the shaft 18 is journaled in a bearing 24 carried by the hopper bottom 3 and to the end of the shaft inside the hopper is secured a feeding disc or the like 25. This is disposed directly over the slot 4 and 90 preferably lies substantially in the same plane. By reference to Figure 1, it will be observed that the shaft 18 is also angularly disposed relative to the center line of the machine, such an arrangement resulting from 100

the type of driving gearing which we employ.

What we claim is:

1. In a machine of the class described, the combination with a frame comprising a pair of longitudinally extending members of a shaft supported thereby, driving means for said shaft comprising a ground wheel and gearing associated therewith on one side thereof, and a housing for said gearing comprising a main section and a cover plate therefor, connected thereto and substantially coextensive therewith, said section and plate together forming a bearing for said shaft, said main section being bolted directly to one of said frame members, and a shaft to which said ground wheel is rigidly secured journaled in said last mentioned housing section.
2. In a machine of the class described, the combination with a frame, of a shaft supported thereby, driving means for said shaft comprising a ground wheel and gearing associated therewith and a housing for said gearing comprising a main section and a cover plate therefor, connected thereto and substantially coextensive therewith, said section and plate forming a bearing for said shaft, said housing projecting laterally, and having a relatively long inclined forward face, whereby when any obstruction is encountered as the machine moves along, either the obstruction or the machine is deflected.

In testimony whereof we affix our signatures.

JOHN A. MCKAY.
PATRICK H. LYNCH.
